KNITTING MACHINE

Karl Richard Lieberknecht, Oberlungwitz, Germany, assignor to Knitting Machines Corporation, a corporation of Delaware

**Application May 26, 1938, Serial No. 210,193
In Germany May 29, 1937**

16 Claims. (Cl. 66—96)

- The present invention relates to improvements in knitting machines, and is herein disclosed as embodied in a flat full-fashioned knitting machine of the general type having a narrowing 5 machine frame and loop lifting implements supported thereon, together with a welt mechanism which is mechanically operable to turn the welt.
- The invention as herein disclosed, is embodied in a multiple section, flat full-fashioned knitting 10 machine fitted with automatic welt mechanism of the general type which comprises a series of welt hooks for taking an initial or setting up course of welt fabric loops from the needles, and for subsequently returning said loops to the 15 needles to close the welt, in which said welt hooks are carried on a swing support mounted on a vertically adjustable pivot rod located directly above the needle series, and in which actuating mechanism is provided for imparting vertical and 20 forward and back swinging movements to said support to take an initial setting up course of welt fabric from the needles to turn the welt. In order to avoid interference between the welt instrumentalities and other operating parts of the 25 machine, particularly the narrowing machine, during the setting-up and subsequent welt turning operations, it is contemplated that the narrowing machine and associated parts will be moved to a high inoperative position in which 30 this mechanism is located out of the path of movement of the welt instrumentalities. During the knitting the welt fabric, it is the usual practice to bring the narrowing machine into active 35 operation for the knitting of one or picot courses, in order to form a decorative design at the top edge of the finished stocking. When such narrowing machine operations are carried out during the knitting of the welt portion of the fabric, the narrowing machine and loop lifting points 40 supported thereby must then be returned to the high or clear position as above described, in order to prevent interference and consequent damage to the machine and to the fabric being knitted thereon.
- 45 It is an object of the present invention to provide in a machine of this general type having a mechanically operating welt mechanism, a safety device which will operate automatically in the event that the narrowing machine has not been moved to its high or clear position, to prevent operation of the welt mechanism which would otherwise result in interference and consequent damage to the machine parts as the welt instrumentalities are moved into operating relation to 50 the needles.

It is more generally an object of the invention to provide in a full-fashioned type knitting machine having knitting devices including a needle series and a plurality of operating instrumentalities arranged to be moved alternatively into operating relationship with the needles for the performance of diverse machine operations auxiliary to knitting, a safety device which is well adapted to prevent operation of the machine in such a manner as to bring one such instrumentality into interfering engagement with another while positioned in operating relation to the needles. 5

With these and other objects in view, as may hereinafter appear, one feature of the invention 15 consists in the provision of a safety device constructed and arranged to be controlled by the position of the narrowing machine including the loop lifting points thereon, and to be rendered operative only at that point in the machine operation 10 at which the welt instrumentalities are to be rendered operative for movement into operative relation to the needles. 20

Another feature of the invention consists in the provision of a safety device which comprises 25 a control element arranged to be actuated by movement of the narrowing machine from its inoperative or clear position, and connections controlled thereby and arranged to be actuated by the welt mechanism to prevent movement of the 30 welt instrumentalities into operative relationship to the needle series.

The several features of the invention consist also in the devices, combinations and arrangement of parts hereinafter described and claimed, 35 which together with the advantages to be obtained thereby will be readily understood by one skilled in the art from the following description taken in connection with the accompanying drawings, in which Fig. 1 is a sectional view of a 40 flat full-fashioned knitting machine looking from the left, only so much of the machine having been shown as is believed necessary to illustrate the connection of the present invention therewith; Fig. 2 is a detail view taken on the line 45 2—2 of Fig. 1, and illustrating particularly the bell-crank trip lever for the safety device; Fig. 3 is a somewhat fragmentary detail view on enlarged scale of certain of the parts shown in Fig. 1 illustrating particularly the manner in 50 which the safety device is moved into operating position when the narrowing machine and picot point bar have been moved downwardly from their high inoperative position; Fig. 4 is an enlarged detail view in front elevation, illustrating 55

particularly the connections for driving the welt mechanism from the main cam shaft and a pattern control for the same; and Fig. 5 is a diagram of certain electrical connections for the main driving motor of the machine including particularly the motor start and stop switch, and a motor slow-down switch.

The drawings disclose a multiple section flat full-fashioned knitting machine which may be 10 of ordinary description, comprising for each knitting section a series of spring beard needles 10 carried on a needle bar 12 supported for movement with relation to a fixed press edge 14, and cooperating knockover bits 16, and sinkers 18. 15 The supporting structure for the machine comprises the usual cross frames 20 located at spaced intervals along the length of the machine, and secured together by lengthwise extending supports including the sinker rail 22, lower rear rail 20 24 and lower front rail 26.

The narrowing machine as generally shown in Fig. 1 of the drawings, comprises a lengthwise extending supporting rod 28 mounted on lever arms 30 for movement about a pivot shaft 32 to 25 move the narrowing machine toward and away from the needles. The usual narrowing points for performing fashioning operations are generally indicated at 34 and are supported on narrowing rods 36 slidably supported in depending 30 bracket 38 secured to the supporting rod 28. The narrowing machine also has supported thereon the usual lace tackle including lace point rods 40, and picot point rod 41 which is slidably supported on extensions of the brackets 38, and carries 35 thereon a picot bar 42 which is arranged to be swung downwardly from the raised inoperative position of Fig. 1 into position for the working of the usual picot markings into the fabric. The mechanism for raising and lowering the narrowing 40 machine for the performance of loop transfer operations comprises a link 43 connected at its upper end to the supporting rod 28, and at its lower end to a rearwardly extending cam lever 44 supported to turn on pivot shaft 45. In order 45 that the narrowing machine may be moved to a high inoperative position out of the path of operation of the welt mechanism hereinafter described, additional manually operable connections are provided which include a hand lever 46 50 supported on the pivot shaft 45, and connected by a link 47 to one arm of a double lever 48, the other arm of which carries a roller 49 which is adapted to engage with and lift the cam lever 44 and narrowing machine connected thereto, to 55 the high inoperative position shown in Fig. 1 of the drawings.

The present machine is also provided with 60 automatic mechanism for setting up an initial course of welt fabric and for turning the welt, which is in many respects similar to that illustrated and described in applicant's copending application Serial No. 76,180 filed April 24, 1936. Certain features of this mechanism including the driving connections hereinafter described 65 form the subject matter of another application shortly to be filed. The welt mechanism comprises a welt bar 51 associated with each knitting section having supported thereon a series of welt hooks 50 which are adapted to remove alternate 70 needle wale kinks of the setting-up course from alternate needles, and subsequently to return these loops to the needles to turn the welt. The hooks 50 and welt bar 51 for each section of the machine, are supported for vertical and forward and back motions on a hanging frame or pendant 75

52 comprising upwardly extending arms secured at their upper ends to a rock shaft 54 which extends through the machine length, and is in turn supported for vertical movements on forwardly extending supporting arms or levers 56 provided 5 at spaced intervals along the machine length. The supporting levers 56 are secured at their rear ends to a rock shaft 58 which is supported to turn in stationary bearings formed on upwardly extending bracket 60 which may be conveniently 10 secured to the usual cross frames 20 of the machine. In the embodiment of the invention illustrated, the desired vertical and forward and back movements are imparted to the pendants 52 and welt hooks 50 in timed relation to the main 15 cam shaft 46 through mechanism which comprises a subsidiary cam shaft 62 extending the length of the machine and supported in bearings formed in the brackets 60. For imparting vertical movements to the pendants 52 and hooks 50, 20 identical vertical motion cams 64 are secured at spaced intervals to the subsidiary cam shaft 62, and are arranged for engagement with rollers 66 mounted on certain of the forwardly extending supporting lever arms 56. Forward and back 25 movements are imparted to the pendants 52 and hooks 50 by means of identical forward and back motion cams 68 secured at spaced intervals to the subsidiary cam shaft 62, and arranged for engagement with cam rollers 70 mounted on 30 rearwardly extending cam levers 72 rigidly secured at their forward ends to the hubs of the hanging frames 52. Tension springs 74 connected to the rear ends of the cam lever 72, act to rock the pendants 52 and hooks 50 yieldingly 35 away from the needles, and to maintain the cam rollers 70 in engagement with the forward and back motion cams 68.

In the illustrated construction, the subsidiary cam shaft 62 is arranged to be driven through 40 one-half revolution only during each of the setting-up and subsequent welt turning operations in timed relation to the main cam shaft of the machine designated at 75. The mechanism through which the subsidiary cam shaft 62 is 45 driven from the main cam shaft 75 comprises a bevel driving gear 76 loosely mounted on the main cam shaft 75 which meshes with a bevel pinion 78 on a connecting drive shaft 80, which in turn drives a second connecting drive shaft 82 50 through bevel gear connections generally indicated at 84. The drive shaft 82 adjacent its upper end carries a bevel pinion 86 adapted to mesh with a bevel gear 88 rigidly secured to the supplemental cam shaft 62. The construction 55 and arrangement of these driving connections is such that the supplemental cam shaft 62 will be driven in a counterclockwise direction as viewed in Fig. 1. In the illustrated construction, the 60 bevel driving gear 76 is driven from the main cam shaft 75 through connections which comprise a single tooth clutch member 90 which is supported to turn with the driving gear 76 and to slide axially with relation thereto, by means of 65 two pins 92 secured to the clutch member 90, and extending axially through bores formed in the hub of the gear 76. The clutch member 90 is arranged for engagement with a cooperating driving clutch member 94 rigidly secured to the 70 main cam shaft 75. A stationary guide member 96 secured to the machine frame, is arranged for engagement with an annular groove 98 formed in the hub portion of the drive gear 76 to prevent axial movement of the gear, and to main- 75

tain a constant meshing relationship of the gear with pinion 78.

The driving clutch member 90 is moved into and out of operative engagement with the driving clutch member 94 to start and stop the rotation of the subsidiary cam shaft 62 by means of connections which comprise clutch shifting levers 100 and 102 secured to a vertically extending rock shaft 104, and provided at their forward 10 ends with follower rolls 106 arranged to engage in an annular groove 108 formed in the periphery of the slidable clutch member 90. A tension spring 110 connected to a laterally extending arm 112 on the lower end of the vertical rock 15 shaft 104, tends to move the single tooth clutch member 90 into operating engagement with the driving clutch member 94. The clutch member 90 is, however, held normally in a retracted inoperative position by the engagement of a vertically extending detent lever 114 carried on a fixed pivot 116 with a rearwardly extending arm 118 secured to the upper end of the vertical rock shaft 104. Upon movement of the detent lever 114 rearwardly out of engagement with the co-operating arm 118, the clutch member 90 will be moved under the pressure of its spring 110 into operative engagement with the driving clutch member 94. After the main cam shaft 46 has rotated through somewhat less than one revolution, when the subsidiary cam shaft 62 has turned through substantially one-half revolution, the clutch member 90 is again moved to its inoperative position to disconnect the drive to the subsidiary cam shaft by the engagement of a roller 120 supported on the upper clutch shifting lever 100 with a throw-out cam 122 on the face of a disk 124 forming part of the driving clutch member 94. The subsequent movement of the detent lever 114 into locking position in engagement with the arm 118, serves to lock the parts in the inoperative position shown, for example, in Figs. 1 and 4.

With the construction shown, the operation of the welt mechanism as above described, is automatically controlled from the usual pattern chain of the machine generally indicated at 126. Connections through which this control is effected, comprise a forwardly extending link 128 secured at its rear end to the detent lever 114, and at its forward end to one end of a bell-crank 130, the other arm of which is connected by means of a link 132 to an upwardly extending arm 134 of a pattern chain lever 136. A tension spring 138 attached to the arm 134 tends to maintain these parts in the position shown in Figs. 1 and 4 to maintain the detent lever 114 normally in locking position.

Following the usual practice in machines of this type, the main cam shaft 75 of the machine is driven from an electric motor generally designated at 140 in the diagrammatic view Fig. 5. This motor as indicated in the diagram referred to, is constructed and arranged to be driven at a plurality of speeds, and is provided with a starting and stopping switch 142, and a slow-down switch 144 which is connected through pattern controls from the pattern chain 126 to cause the machine to be automatically slowed during the operation of the welt mechanism to take an initial setting-up course of loops from the needles, and subsequently to return these loops to the needles to turn the welt. Inasmuch as the driving connections from the motor 140, and the construction of pattern controls for the switches illustrated, are well known

in the prior art, and form specifically no part of the invention, illustration of these parts in detail has been omitted.

In accordance with the present invention, a safety device is provided which will act to prevent possible interference of the automatically operated welt mechanism above described, with parts of the narrowing machine, in the event that the narrowing machine has not been moved into its high inoperative or clear position prior to the time when the welt hooks 50 are moved rearwardly into operating relationship to the needles to transfer the loops held thereon back to the needles, and thereby to turn the welt. As best shown in the drawings, the safety device comprises connections which are arranged to be operated from the welt mechanism, and which act when rendered operative to stop the machine. These connections comprise specifically a cam 146 secured to the subsidiary cam shaft 62 which is arranged to engage with a roller 148 carried on a cam actuated lever 150 supported on a fixed pivot 152 and connected at its rear end to a downwardly extending link 154. The link 154 passes downwardly through a slotted portion 156 formed in one arm of a bell-crank 158, and at its lower end carries a pair of adjustable stop nuts 160 which are arranged to cooperate alternatively with two steps 162 and 164 formed in the under side of the bell-crank 158. The downwardly extending arm of the bell-crank 158 is connected by means of a link or control rod 166 to the starting and stopping switch 142 for the machine motor 140, so that actuation of the bell-crank 158 in a counterclockwise direction from the position shown in Fig. 2, will operate to shift the switch to stop position and stop the machine. The reciprocatory movement imparted to the vertically extending link 154 from the cam 146, is limited to cause the nuts 160 to engage with and rock the bell-crank 158 only when the link 154 is located in its innermost position with the nuts 160 located beneath the step 164 as shown in Fig. 3.

Movement of the link 154 laterally about its pivotal connection with the lever 150 is controlled to render the connections above described operative or inoperative to stop the machine, by means of a control element in the form of a rod 168 which is slideably supported in two lugs 170 and 172 mounted in a stationary part of the machine frame. A tension spring 174 connected at one end to the lug 172 and at its other end to a collar 176 on the control rod 168, tends to move the link 168 forwardly to an operative position in which the nuts 160 are located beneath the lower step 164. A collar 178 on the link 168 is arranged to engage against the lug 172 to limit the forward movement of the link under the pressure of its spring 174.

The control rod 168 is arranged to be acted upon by the narrowing machine frame when moved to its high inoperative or clear position to move the control rod 168 rearwardly or to the left as shown in Fig. 1, to render the safety device inoperative. To this end a lug 173 is mounted on the pivot rod 42, and is arranged when the pivot bar is swung upwardly to the inoperative or full line position shown in Fig. 1, and when the narrowing machine has been moved to its high position, to engage with and move the control rod 168 to the left against the pressure of the spring 174. The lug 173 is provided with a cam-shaped surface 180 for engagement with the control rod 168, so that if the pivot bars 42

are swung to inoperative position prior to the movement of the narrowing machine frame to its high clear position, this movement of the narrowing machine will operate automatically to 5 shift the control rod 168 rearwardly to render the safety device inoperative as above described.

The operation of the safety device to prevent 10 operation of the welt mechanism to return the initial course of welt fabric to the needles until the narrowing machine has been moved to its high 15 inoperative position, may be described as follows: Prior to the starting of a new set on the machine, the welt hooks 50 are located directly above the needles 10, as shown in full lines in Fig. 1, the narrowing machine frame 28 being at this time supported in its high inoperative position and with the picot point bar 42 raised. For this position of the parts, the safety device is supported in its inoperative position through the engagement 20 of the control rod 168 with the cam surface 180. During the subsequent operation of the machine to set up and knit the welt fabric, the welt hooks 50 are moved forwardly in the line of take-up away from the needles, so that the narrowing machine may be moved downwardly 25 from its high position, and the picot bar 42 placed in its operating position, as shown in Fig. 3. As previously pointed out, either the downward movement of the narrowing machine frame or 30 the movement of the picot bar 42 from its inoperative position, will operate to shift the link 154 forwardly into its active locking position in which the stop nuts 160 are located against the lower stepped surface 164 of the bell-crank trip lever 158. The safety device does not, however, at this 35 time become operative, due to the fact that the auxiliary cam shaft 62 is stationary. If for any reason the operator neglects to return the narrowing machine and picot point bar 42 to their high inoperative positions shown in Fig. 1, prior 40 to the operation of the welt mechanism to return the fabric loops to the needles, the start of the rotation of the auxiliary cam shaft 62 through its second half revolution, will cause the connections controlled by cam 146 including lever 150, link 154, and bell-crank 158, to shift the start and stop switch 142 to stop position, thus 45 stopping the machine. Inasmuch as the machine during the operation of the welt mechanism is operated at half speed through the operation of the slow-down switch 144, as above described the shutting off of the motor 140 will operate instantly to stop the machine prior to the rearward 50 movement of the welt hooks 50 into interfering engagement with the narrowing machine.

55 While applicant's safety device is herein disclosed in a preferred form as applied to prevent movement of the welt hooks 50 into interfering engagement with parts supported on the narrowing machine frame 28, it will be understood that the invention in its broader aspects is not limited to the specific construction and arrangement shown, but may be equally well applied for the control of other than welt mechanism instrumentalities performing machine operations auxiliary to knitting, which might be brought into interfering engagement with other such instrumentalities which may or may not be directly supported on the narrowing machine frame.

70 The invention having been described, what is claimed is:

1. In a flat knitting machine have knitting devices including a needle series, a plurality of operating instrumentalities constructed and arranged to cooperate with the needles for the

7 performance of diverse machine operations auxiliary to knitting, including instrumentalities for turning a welt, actuating means for said welt instrumentalities, and other instrumentalities for the performance of other of said auxiliary operations, means for supporting said other instrumentalities adapted for positioning the same in an inoperative position out of the path of movement of the welt instrumentalities, and a safety device controlled by said other instrumentalities 10 to prevent movement of said welt instrumentalities into interfering engagement therewith.

2. In a flat knitting machine having knitting devices including a needle series, a plurality of operating instrumentalities constructed and arranged to cooperate with the needles for the performance of diverse operations auxiliary to knitting, including a narrowing machine, means for moving said narrowing machine to a high inoperative position, actuating means for moving other 15 of said instrumentalities into cooperative relation to the needles for the performance of other of said auxiliary operations, and a safety device controlled by the narrowing machine to prevent movement of other of said instrumentalities into 20 interfering engagement therewith.

3. In a flat knitting machine having knitting instrumentalities including a needle series, a plurality of operating instrumentalities for the performance of diverse machine operations auxiliary 30 to knitting, including a welt mechanism and means for actuating said mechanism to turn the welt, a narrowing machine, and a support on which the narrowing machine is movable to an inoperative position out of the path of movement 35 of the welt instrumentalities, and a safety device controlled by the narrowing machine to prevent movement of the welt mechanism into interfering engagement therewith.

4. In a flat knitting machine having knitting 40 instrumentalities including a needle series, a plurality of operating instrumentalities for the performance of diverse machine operations auxiliary to knitting, including a welt mechanism and means for actuating said mechanism to turn the welt, a narrowing machine, and a support on 45 which the narrowing machine is movable to an inoperative position out of the path of movement of the welt instrumentalities, and a safety device controlled by the narrowing machine and arranged to act on said actuating means to prevent movement of the welt mechanism into interfering 50 engagement therewith.

5. In a flat knitting machine having knitting 55 instrumentalities including a needle series, a plurality of operating instrumentalities for the performance of diverse machine operations auxiliary to knitting, including a welt mechanism and means for actuating said mechanism to turn the welt, a narrowing machine, and a support on 60 which the narrowing machine is movable to an inoperative position out of the path of movement of the welt instrumentalities, and a safety device comprising connections constructed and arranged to be rendered operative by movement of the 65 narrowing machine from said inoperative position to arrest the operation of said actuating means.

6. In a flat knitting machine having knitting 70 instrumentalities including a needle series, a plurality of operating instrumentalities for the performance of diverse machine operations auxiliary to knitting, including a welt mechanism and means for actuating said mechanism to turn the welt, a narrowing machine, and a support on 75

- which the narrowing machine is movable to an inoperative position out of the path of movement of the welt instrumentalities, and a safety device comprising a control element actuated by movement of the narrowing machine from said inoperative position, and connections controlled by said element actuatable by said actuating means to arrest the operation of said actuating means.

5 7. In a flat full-fashioned type knitting machine, the combination of knitting devices including a needle series, a narrowing machine and loop lifting points supported thereby movable into and out of operating position, a welt mechanism mechanically operable to turn the welt, and

10 15 a safety device constructed and arranged to prevent operation of said welt mechanism with the loop lifting points in operative position.

8. In a flat full-fashioned type knitting machine, the combination of knitting devices including a needle series, a narrowing frame having loop lifting points to cooperate with the needles movable to and from a high inoperative position with relation to the needle series, a welt mechanism comprising welt instrumentalities

20 25 movable into operative relationship to the needle series to receive an initial course of welt fabric, and subsequently to turn the welt, actuating means for said welt instrumentalities, and means rendered operative by movement of the loop lifting instrumentalities from inoperative position to prevent movement of the welt instrumentalities into operative relation with the needles.

9. In a flat knitting machine having knitting instrumentalities including a needle series, a plurality of operating instrumentalities for the performance of diverse machine operations auxiliary to knitting, including a welt mechanism and means for actuating said mechanism to turn the welt, a narrowing machine, and a support on

30 35 40 which the narrowing machine is movable to an inoperative position out of the path of movement of the welt instrumentalities, and a safety device comprising connections constructed and arranged to be rendered operative by movement of the loop lifting instrumentalities from inoperative position to prevent movement of the welt instrumentalities into operative relation with the needles.

45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910

- for imparting vertical and swinging movement to said pendant support, means for driving the supplemental shaft through successive increments of rotation for the performance of the loop taking and welt turning operations, and a safety device comprising a control element actuated by movement of the loop lifting points from inoperative position, and connections controlled thereby including a cam on said cam shaft and a follower arranged to be actuated by said cam upon rotation of said supplemental cam shaft to arrest rotation of the cam shaft whereby said welt instrumentalities are prevented from moving into operative relationship to the needle series.
15. In a flat full-fashioned type knitting machine, the combination of knitting devices including a needle series, a narrowing frame and loop lifting points supported thereby means for moving the narrowing frame to a high inoperative position with relation to the needle series, a welt mechanism comprising welt instrumentalities movable into and out of operative relationship to the needle series to receive an initial course of welt fabric, and subsequently to turn the welt, actuating means for said welt instrumentalities acting when rendered operative for moving said instrumentalities to take effect the taking of the initial welt course and the subsequent closing of the welt, and a safety device comprising a member continuously actuated during operation of said actuating means, a machine stop control arranged to be actuated thereby, and a control element actuatable by movement of the loop lifting points from inoperative position for operatively connecting said reciprocating member with the stop control to stop the machine whereby said welt instrumentalities are prevented from moving into operating relationship to the needle series.
16. In a flat full-fashioned type knitting machine, the combination of knitting devices including a needle series, a narrowing frame and loop lifting points supported thereby movable into and out of operating position with relation to the needle series, a welt mechanism comprising welt instrumentalities movable into and out of operative relationship to the needle series to receive an initial course of welt fabric, and subsequently to turn the welt, actuating means for said welt instrumentalities acting when rendered operative for moving said instrumentalities to effect the taking of the initial welt course and the subsequent closing of the welt, and a safety device comprising a member continuously actuated during operation of said actuating means, a machine stop control, a control element normally acting to move said reciprocating member into operative relation to said stop control, and an abutment supported on said narrowing frame arranged for the inoperative position of the loop lifting points to act on said control element to maintain said reciprocating member out of engagement with said stop control.

KARL RICHARD LIEBERKNECHT.
